UNITED STATES PATENT OFFICE.

HENRY A. L. LIBAIRE, OF NEW YORK, N. Y.

CUFF-BUTTON.

SPECIFICATION forming part of Letters Patent No. 626,433, dated June 6, 1899.

Application filed March 24, 1899. Serial No. 710,324. (No model.)

To all whom it may concern:

Be it known that I, HENRY A. L. LIBAIRE, of New York city, county and State of New York, have invented new and useful Improvements in Cuff-Buttons, of which the following is a specification.

This invention relates to a separable cuff-button which is made springless and so formed that the elasticity of the cuff itself will prevent the two sections of the button from becoming accidentally separated.

In the accompanying drawings, Figure 1 is a perspective view of a cuff provided with my improved button; Fig. 2, a top view thereof; Fig. 3 a detail perspective view of the two parts of the button, showing them separated.

The letters a a' represent the two heads of the button secured at an inclination to a stem b and a tube c , respectively. The stem b is of a diameter to fit into the tube and carries a laterally-projecting pin b' . The tube c is provided with a bayonet-slot c' , which merges into a return-pocket c^2 . At the free end of the tube c there is formed a collar or flange d , which is cut away opposite the slot c' , so that the latter is accessible to the pin b' . The slot c' extends only along the inner part of the tube c , and the pin b' is placed at a distance from the end of the stem b . Thus when the two sections of the button are assembled the tube will telescope the inner end of the stem only, while the outer end of the stem remains exposed, and consequently the collar d will be placed at a distance from each of the heads a a' .

In use the stem b and tube c are slipped through the two buttonholes of the cuff A , and the stem is pushed into the tube and rotated, so that the pin b' passes through the slot c' into the pocket c^2 , when the parts will be properly connected. In this closed position one flap A' of the cuff will be supported upon the stem b and bear normally against

the head a , while the other flap A^2 will be supported upon the tube c and bear normally against the head a' . Thus the natural elasticity of the cuff will tend to force the two parts of the cuff-button outward in opposite directions, so that the pin b' is prevented from becoming unseated. If, however, either of the flaps A A^2 is subjected to outside pressure, as when the wearer bears upon the cuff in writing, the flaps would be apt to be pushed off the inner ends of their respective seats b and c and upon the seat of the other flap; but as the button is made springless this displacement of the cuff would remove the outward pressure against the heads a a' and would render the parts b c liable to become separated. This tendency is, however, overcome by the separating-flange d , which confines each cuff-section to its seat and prevents it from passing over the edge thereof and upon the adjoining seat. Moreover, if the sections do become separated the flange d will hold the section c a' securely suspended from flap A^2 , while the pin b' will hold the section b a securely suspended from flap A' .

To open the button, it is only necessary to force the heads inwardly against the resiliency of the cuff and to then turn one of the parts, so as to disengage the pin b' from the slot c' c^2 .

What I claim is—

In a springless cuff-button, the combination of stem b having inclined head a , and pin b' , set back from the end of the stem, with tube c , having inclined head a' , and a bayonet-slot c' , c^2 , that extends along the inner end of the tube only, and with a collar d , mounted on said inner end and cut away opposite to slot c' , substantially as specified.

HENRY A. L. LIBAIRE.
